(51) **LOC (15) Cl.** **24-01**

(57) **CLAIM**

(52) **U.S. Cl.**

The ornamental design for a percussion massager, as shown and described.

USPC **D24/215**

DESCRIPTION

(58) **Field of Classification Search**

FIG. 1 is a top, perspective view of the front and left side of a percussion massager of the present design.

USPC D24/200, 209, 211, 212, 213, 214, 215;

FIG. 2 is a bottom, perspective view of the rear and right side of the percussion massager of FIG. 1.

D8/14.1; D28/13, 44

FIG. 3 is a side elevation view of the left side of the percussion massager of FIG. 1.

CPC A61H 23/006; A61H 2201/0157; A61H

FIG. 4 is a side elevation view of the right side of the percussion massager of FIG. 1.

2201/0153; A61H 7/003; A61H 7/005;

FIG. 5 is a front elevation view of the percussion massager of FIG. 1.

A61H 15/0085; A61H 23/00; A61H

FIG. 6 is a rear elevation view of the percussion massager of FIG. 1.

2201/0165

FIG. 7 is a top plan view of the percussion massager of FIG. 1; and,

See application file for complete search history.

FIG. 8 is a bottom plan view of the percussion massager of FIG. 1.

In the drawings, the broken lines depict portions of the percussion massager that form no part of the claimed design.
